UNITED STATES PATENT OFFICE.

FRANK A. ADKINS, OF CHICAGO, AND NOAH S. HARTER, OF WAUKEGAN, ILLINOIS,
ASSIGNORS TO CHAMPION FOLDING FURNITURE COMPANY, OF WAUKEGAN, ILLINOIS,
A CORPORATION OF ILLINOIS.

FOLDING BED.

Application filed July 15, 1927. Serial No. 206,097.

This invention relates to improvements in portable folding beds, adapted for camping purposes, and more particularly to a type of bed wherein the side rails and legs of the bed are composed of channel bars, each side rail composed of a central bar and pivoted end bars which fold within the central bar, and the legs being adapted to fold around the back and sides of the central bar. The present invention relates more particularly to the means for fastening the legs to the end bars of the side rails, whereby the bed fabric may be stretched taut, after the bed has been set up, with a minimum of effort, and whereby the stretching devices fold within end bars of the side rails; also to improvements in the leg ties which extend between the legs attached to each side rail, and to the construction of the side rails, whereby the ties fold in grooves in the backs of said rails; also to improvements in the forms of the several channelled parts, whereby said parts fold and unfold with a minimum amount of friction, and to certain other details of construction which will be hereinafter pointed out.

In the accompanying drawing,

Fig. 1 is a top plan view of the folding bed frame, set up;

Fig. 2 is a side elevation of the same;

Fig. 3 is an end elevation taken at the right of Fig. 2;

Fig. 4 is a section on the line 4—4 of Fig. 1, on a larger scale;

Fig. 5 is a section on the line 5—5 of Fig. 6;

Fig. 6 is a section on the line 6—6 of Fig. 5;

Fig. 7 is a perspective view of one of the hinged sections of a leg brace;

Fig. 8 is a top plan view of the bed frame, folded;

Fig. 9 is a bottom plan view of the same;

Fig. 10 is a section the same as in Fig. 4, showing some of the parts in detail; and,

Fig. 11 is a top plan view of a part of one of the side rails, showing an end section and latch folded within the central section.

The bed frame comprises side rails *a* and *a'*, of channel steel, each side rail composed of a relatively long central bar 1 and end bars 2 and 2^a, which are pivotally connected to the central bar. Within the end bars, at their outer ends, are arranged adjustable extensions *c*, adapted to engage end bars on a fabric indicated in dotted lines at *d*. These

extensions are likewise of channelled steel, 55 each extension laid with one side against the back wall of an end bar, as shown in Figs. 4 and 6, one side of each extension-piece being cut off, as indicated at *c'*, to form a stop and the other side of the extension-piece being 60 extended beyond this stop, as shown at *c''*, to enter a slot in an end bar of the fabric. Each central bar has legs 3, pivotally connected to its ends. The end bars are pivoted within the central bars upon pivots 4, and 65 when the bed is set up the channelled sides of the central bars face upwardly, and the channelled sides of the end bars face downwardly, as shown in Figs. 1 and 4. The legs are forked at their upper ends so as to fit against 70 the outer sides of the central bar, and pivot pins 5 secure the legs to the central bars. The channelled sides of the legs at opposite ends of a central bar face one another when the bed is set up. Each end bar folds within 75 the central bar, as shown in Figs. 5, 6, 8 and 11, with its channelled side facing the same way as the central bar, and each leg folds around the back and sides of the central bar, as shown in Figs. 5 and 9. The legs attached 80 to each side rail are connected together about midway of their lengths by a tie *b*, comprising three sections, namely, a relatively long central section 6, composed of a flat metal band, and end sections 7, the latter being 85 secured to the legs by pivot pins 8. As shown in Figs. 7 and 10, each end section comprises a flat bar having central longitudinal slots 7^a and 7^b, and having parts 7^c and 7^d struck 90 up from the metal to provide openings through which the pivot pin 8 may be inserted to secure the section to the leg. The end of each section adjacent its pivotal point is bent over at right angles to the body of 95 the section to form a stop 7^e. When the bed is unfolded, the stops 7^e rest against the back walls of the legs, as shown in Figs. 4 and 10, and these stops prevent the end sections of the ties from sagging downwardly below their pivotal points while the bed is being 100 folded or unfolded. When the bed is folded, the end sections 7 of the ties lie within the legs, as shown in Figs. 5 and 6, and the central ribbonlike sections 6 lie within shallow 105 grooves 1^a, which are formed in the backs of the central bars of the side rails, and extend throughout the lengths of said bars. The stops 7^e bear against the backs of the central

bars of the side rails, at each side of the section 6 of the tie, as shown in Figs. 5 and 6.

The latches 9 and 9^a, pivoted within the end bars 2 and 2^a, are adapted to engage the 5 pivots 8 to fasten the end bars to the legs. These latches extend through slots 3^a in the backs of the legs and through the slots 7^b in the sections 7 of the leg ties, and each latch has at its free end a hooked portion 9^b for 10 engaging the pivot pin 8. The latches 9^a are mounted directly upon pivot pins 10 in the end bars 2^a. The latches 9, as shown in Figs. 4, 6, 8 and 10, are not pivoted directly to the end bars 2, but each of said latches is 15 connected by a pivot pin 10^a, to a channeled lever 11, which lever has one end connected by a pivot pin 12 to an end bar. When the lever is in the position shown in Fig. 4, the pivot pins 8, 12 and 10 are practically in a 20 straight line, with the pivot pin 12 upon which the lever is fulcrumed between the two other pivots. When the lever 11 is moved downward toward the latch 9, the pivot 10 swings about the pivot 12 and this causes the 25 latch 9 to move endwise to release its hook from the pivot pin 8. By returning the lever to the position shown, it is evident that the latch will be moved in the opposite direction, and the end section 2 of the side rail 30 will be drawn downward, until the pivot pin 10^a is in line with the pivots 12 and 8, when the lever 11 will be locked. It will be understood that the fabric *d*, indicated in dotted lines in Fig. 2, engages the adjustable ends 35 of the end bars 2 and 2^a, and that in setting up the bed the latches are hooked over the pivot pins 8 on the legs and the levers 11 are then moved into the position illustrated in Figs. 2 and 4, and this has the effect 40 of stretching the fabric and holding the legs in their outer positions.

The legs at each end of the bed are connected together by crossed brace rods, each rod comprising a long section 14, pivotally 45 connected to the upper end of a leg, and a shorter section 14^a, pivotally connected to the lower end of a leg. The longer sections are pivoted at their crossing points, as shown at 50 15, and a toggle 16 is connected by pivots 18 and 19 to the sections 14. Stops 20 on the sections 14 limit the downward movement of the toggle.

When the bed is set up, as shown in Figs. 1-4, the legs are tied together and held from 55 spreading by the ties *b*. The fabric applies spring tension to the end sections of the side rails, tending to lift the same, but these are held down by the latches 9, which fasten the end sections to the legs. In setting up the 60 bed, final tension is given to the fabric by raising the levers 11 to the positions shown, which results in drawing the end sections downwardly toward the legs.

In folding the bed, the toggles 16 at the 65 ends of the bed are broken by pulling up-

wardly upon them, and the crossed bars are folded by breaking the joints between their sections 14 and 14^a downwardly, and the opposite side rails and legs of the bed may then be brought close together. By moving the hand levers 11 downwardly, the latches 9 will be released from the pivots 8 on the legs and the tension on the fabric will be relaxed so that the latter may be removed from the end sections of the side rails. The 70 end sections are then folded back into the central sections and the latches 9 and 9^a are folded into the end sections, as illustrated in Figs. 5, 6 and 8. The levers 11 will also fold within the end sections as illustrated in the 75 views just mentioned. The sections 7 of the leg ties fold upwardly within the legs, and the latter are then folded over and around the backs of the central sections, and the sections 6 of the leg ties then lie within the grooves 80 1^a in the backs of the central sections of the side rails. The crossed braces, which are pivotally connected to the legs, and the toggles fold as shown in Fig. 9, against the backs 85 of the legs and close to the central sections 90 of the side rails. When the bed is completely folded, as shown in Figs. 5 and 9, it occupies very small space.

In order to avoid unnecessary friction between the channeled folding parts, the end bars of the side rails are wide enough to fit closely against the side walls of the central bars only at their pivotal ends, the major portions of the end bars being narrower so that they do not touch said side walls, as shown 95 in Figs. 5 and 8; also, the levers 11 engage the side walls of the end bars only at their pivotal ends, and the legs 3 fit against the central bars only at their pivotal ends, as 100 shown in Fig. 5.

What we claim is:

1. A folding bed comprising side rails and legs composed of channel bars, each rail comprising a relatively long central bar, the legs pivoted to the ends of the central bars and adapted to fold around the backs and sides thereof, and a leg tie connecting the legs attached to each central bar, each tie comprising relatively short end sections pivoted within the legs and adapted to fold upwardly 115 therein, and a relatively long central section adapted to lie against the back of the central section of the side rail when the bed is folded.

2. A folding bed comprising side rails and legs composed of channel bars, each rail comprising a relatively long central bar having a groove in the outer side of its back wall, the legs pivoted to the ends of the central bars and adapted to fold around the backs and sides thereof, and a tie connecting the legs attached to each central bar, each tie comprising relatively short end sections, pivoted within the legs and adapted to fold upwardly 120 therein, and a relatively long central 125 section.

section adapted to lie within the groove in the central bar when the bed is folded.

3. A folding bed comprising side rails and legs composed of channel bars, each rail comprising a relatively long central bar having a groove in the outer side of its back wall, the legs pivoted to the ends of the central bars and adapted to fold around the backs and sides thereof, and a tie connecting the 10 legs attached to each central bar, each tie comprising relatively short end sections, pivoted within the legs and having parts at their inner ends adapted to abut against the backs of the legs to limit the downward movement 15 of said sections, and a relatively long central section adapted to lie within the groove in the central bar when the bed is folded.

4. A folding bed comprising side rails and legs composed of channel bars, each side rail 20 comprising a central bar and pivotally connected end bars adapted to fold within the central bar and to project beyond the same when the bed is set up, levers pivoted within the end bars at one end of the bed, latches 25 pivoted to said levers eccentrically to the axes of the latter and adapted to interlock with parts on the adjacent legs, latches pivoted within the end bars at the opposite end of the bed and adapted to interlock with the 30 adjacent legs, and a fabric detachably connected to the end bars at both ends of the bed.

5. A folding bed comprising side rails and legs composed of channel bars, each side rail 35 comprising a central bar and end bars pivoted within the central bar, the end bars adapted to fold within the central bar with their channeled sides facing in the same direction, the legs adapted to fold around the

backs and sides of the central bar, latches 40 for engaging the legs pivoted within the end bars and adapted to fold therein, and channeled levers pivoted within two of said end bars and pivotally connected to the latches therein, said levers adapted to fold over the 45 latches.

6. A folding bed comprising side rails and legs composed of channel bars, each side rail comprising a central bar and end bars pivoted within the central bar, the end bars 50 adapted to fold within the central bar with their channeled sides facing in the same direction, the legs adapted to fold around the backs and sides of the central bar, latches for engaging the legs pivoted within 55 the end bars and adapted to fold therein, and channeled levers pivoted within two of said end bars and pivotally connected to the latches therein, said levers adapted to fold over the latches, the side walls of the levers 60 fitting closely against the side walls of the end bars at the pivotal ends of the levers only.

7. A folding bed comprising side rails and legs, each side rail comprising a central bar and pivotally connected end bars adapted to 65 project beyond the central bar when the bed is set up, a fabric connected to the ends of the bars, latches pivotally supported on the end bars and adapted to interlock with parts on the adjacent legs, and levers on the end 70 bars adapted to apply tension to the latches after they have been locked to the legs to draw the end bars downwardly and thereby stretch the fabric.

In testimony whereof we hereunto affix 75 our signatures.
